PLASTIC DOILY CENTERPIECE CONSTRUCTION
 Raymond R. Ciprotti, Leominster, Mass., assignor to
 Plasticraft of Leominster, Inc., Leominster, Mass., a
 corporation of Massachusetts

Filed June 6, 1961, Ser. No. 115,259
 3 Claims. (Cl. 161—37)

This invention relates to a new and improved doily centerpiece comprising a novel arrangement for assembling a plurality of lacy molded plastic doilies such as appear in applications Serial No. D. 59,269, filed February 4, 1960, and Serial No. D. 59,270, filed February 4, 1960; and the principal object of the invention resides in the provision of such a centerpiece or other attractive display comprising a relatively large plastic doily used as a base or flat mat in combination with a plurality of smaller doilies or the like which are folded in a certain manner and temporarily attached about the periphery of the mat or base doily in such a way as to provide an annular centerpiece which has the central portion of the mat or base doily clear as a center surrounded by an annular wall of upstanding folded doilies of smaller size; and the provision of a new and improved fastener or clip for this purpose by which means the doilies are assembled and held in position in the particular manner to be described more fully hereinafter.

Other objects and advantages of the invention will appear hereinafter.

Reference is to be had to the accompanying drawings, in which

FIG. 1 is a perspective view which illustrates the base or mat doily together with one attached smaller doily therefor;

FIG. 2 is a plan view of a fastener clip on a larger scale;

FIG. 3 is an edge view of the fastener of FIG. 2;

FIGS. 4 and 5 illustrate the folds in the doily to be applied; and

FIG. 6 is a diagrammatic view illustrating the application of a small doily to a portion of the large doily.

In carrying out this invention, the same consists in general of a relatively large plastic doily which is generally indicated by the reference character 10 in FIG. 1 and there are a series of possibly ten to twenty smaller doilies which are to be folded and attached peripherally with respect to the doily 10 in the manner to be described in the invention. In FIG. 1 there is shown one of these doilies so attached but it is to be understood that the smaller doily which is attached to the base doily 10 and is indicated at 12 is to form an annular ring completely around the base doily 10, leaving a relatively large portion thereof in the center unimpeded for the application thereto of flower holders, ornamental centerpiece designs, etc., the annularly arranged doily combination of the present invention forming a kind of three-dimensional border therefor.

Both doilies 10 and 12 per se very closely resemble real or factual textile doilies but in fact are molded of plastic material and comprise mainly a great deal of openings any one of which can be selected to carry out the fastening of the smaller doilies to the larger main base doily as will be described.

The fastener clip is illustrated herein in FIGS. 2 and 3 and comprises a relatively small flat elongated plastic

2

member indicated at 14 having a hole 16 at one end and a cooperating snap fastener head 18 at the opposite end. This member is shown in FIG. 1 and the relative sizes of this fastening clip with respect to the two doilies is therefore apparent.

In order to make the plastic doily centerpiece of the present invention, a small doily which is indicated in FIGS. 4 and 5 as at 20, and which is shown folded centrally, is folded again centrally so that it is a four-layer 10 quarter size doily as indicated at 22 in FIG. 5. With the doily as folded in FIG. 5 held rather tightly by the fingers so that the inherent resilience of the plastic material will not cause it to open up and go back to its original flat shape, the clip 14 is inserted through a selected opening or openings in the lace as indicated at 24 as perhaps best seen in FIG. 6. This clip 14 may be inserted in any opening but it has been found that it is better to use one which is a short distance from the center or corner 26 of the folded doily.

With the clip in this position as shown in FIG. 6, it is then extended through selected holes of the main base doily of FIG. 1 and it has been found that it is best to use for instance the holes at 28 and 30 which appear at the base of triangles 32 in the base main doily of FIG. 1. 25 It will be seen that this has been done with respect to the folded doily 12 shown in FIG. 1 which is secured to the main base doily 10 by means of the strip or clip 14.

This action is repeated until the entire circumference of the main or base doily 10 is completely surrounded by such folded and clipped on doilies 12, and thus a beautiful centerpiece arrangement is quickly and easily provided very inexpensively, the same forming a frame for flower holders and ornamental centerpieces of all kinds.

Since the main doily and the other doilies are provided in different sizes and shapes, different kinds of centerpieces are easily made by the user of this invention.

Having thus described my invention and the advantages thereof, I do not wish to be limited to the details herein disclosed, otherwise than as set forth in the claims, but

what I claim is:

1. A doily centerpiece comprising a flat base doily of relatively large diameter, said doily being provided with apertures adjacent the periphery thereof, a series of relatively smaller doilies folded on themselves at the center portions thereof, and a clip for each doily, said clip being flexible and passing through the folds of the smaller doily and through a pair of spaced folds near the periphery of the flat base doily, holding the folded smaller doilies thereto at the periphery of the flat base doily, each elongated clip having an aperture at one end thereof and an enlarged head at the opposite end thereof, the head being of a size to snap into the aperture in the clip providing mating snap fastening means at the respective ends of the clips to form a continuous loop of each clip to hold its respective smaller doily to the flat base doily.

2. A doily centerpiece as set forth in claim 1 wherein the main portion of the smaller doily extends outwardly radially with respect to the peripheral edge or circumference of the main base doily.

3. A doily centerpiece as set forth in claim 1 including a plurality of the smaller folded doilies attached to the main base doily around the rim thereof and extending radially outwardly therefrom, and a strip or clip connecting each said smaller folded doily to the base doily adjacent the periphery thereof.
